(57) **CLAIM**

The ornamental design for a tire, as shown and described.

DESCRIPTION

FIG. 1 is a front right perspective view of a first embodiment of a tire showing our new design, the design repeated about the circumference of the tire;

FIG. 2 is a front elevation view thereof, the design repeated about the circumference of the tire;

FIG. 3 is a right elevation view thereof, the left elevation view being identical;

FIG. 4 is a partial sectional view taken along line 4-4 in FIG. 2;

FIG. 5 is a front right perspective view of a second embodiment of the tire showing our new design, the design repeated about the circumference of the tire, it being understood that the dashed lines form no part of the claimed design, it also being understood that the dash-dot line represents a boundary line, radially inward of which is not part of the claimed design;

FIG. 6 is a front elevation view thereof, the design repeated about the circumference of the tire, it being understood that the dashed lines form no part of the claimed design;

FIG. 7 is a right elevation view thereof, the left elevation view being identical, it being understood that the dashed lines form no part of the claimed design, it also being understood that the dash-dot line represents a boundary line, radially inward of which is not part of the claimed design; and,

FIG. 8 is a sectional view taken along line 8-8 in FIG. 6, it being understood that the dashed lines form no part of the claimed design.
